CLAIM

The ornamental design for a shoe, as shown and described.

DESCRIPTION

FIG. 1 is a bottom front perspective view of a shoe showing my new design;

FIG. 2 is a bottom view thereof; and,

FIG. 3 is a bottom rear perspective view thereof.

The broken lines immediately adjacent to the shaded area define the bounds of the claimed design and form no part thereof. The contrast in shading represents a contrast in appearance only and does not represent any particular color, material, texture, or finish. The broken lines depicting the remainder of the shoe form no part of the claimed design.
